UNITED STATES PATENT OFFICE.

HERBERT McCORNACK, OF WEST CHESTER, PENNSYLVANIA.

CARBURETER.

1,141,570.

Specification of Letters Patent.

Patented June 1, 1915

Application filed August 15, 1910. Serial No. 577,144.

To all whom it may concern:

Be it known that I, HERBERT McCORNACK, a citizen of the United States, residing at West Chester, in the county of Chester and State of Pennsylvania, have invented a new and useful Improvement in Carbureters, of which the following is a specification.

This invention relates to automatic carbureters of the type which are used for supplying the fuel to internal combustion engines.

The objects of the invention are to produce an efficient, reliable and practical carbureter which will effect a thorough carburetation of the air and automatically maintain the proper proportions of the explosive mixture notwithstanding variations in the atmospheric conditions and in the speed and load of the engine and changes in the level of the liquid fuel in the carbureter due to changes in the position of the latter, as when used on motor vehicles; also to accomplish these results without the employment of mechanically operated devices and without the necessity for accurate adjustments; also to separate the excess unvaporized liquid fuel from the carbureted air and prevent it from being carried into the engine cylinder; also to return this unvaporized fuel to the incoming liquid fuel supply and cause it to be again discharged into the incoming current of air and to use the excess liquid fuel, separated from the mixture, to regulate or affect the liquid fuel supply; also to construct the carbureter so that the discharge orifice of the fuel supply nozzle can be made of a size such that it will not be clogged or its action affected by particles of dirt or water in the liquid fuel; also to effectually free the air from dust before carbureting it; and also to improve the construction of carbureters in the respects hereinafter described and set forth in the claims.

These results are attained as follows: The carbureter is provided with a mixing chamber in which the mixture of air and liquid fuel is caused to whirl or rotate rapidly so that the excess fuel, or liquid which is not vaporized, will be thrown outwardly against the walls of the mixing chamber by centrifugal force and separated from the explosive mixture, which is taken axially out of the mixing chamber. The excess fuel thus separated from the air is returned to the fuel supply and again discharged into the

air, the less volatile liquid, which is not readily vaporized, being in this way circulated and reused until it is finally volatilized. The walls of the mixing chamber are preferably heated and this heat supplemented by the intimate frictional contact of the rapidly rotating air in the mixing chamber with the less rapidly rotating film of fuel on the walls of the chamber insures a practically complete vaporization of the less volatile portions of the fuel which otherwise would not be vaporized. Thus while the air is thoroughly carbureted the unvaporized liquid is separated from the mixture with the result that the waste of fuel and the fouling of the cylinder is reduced to the minimum. The excess liquid fuel separated from the air is preferably returned to the fuel supply nozzle so as to regulate or affect the supply of fuel to the carbureter, and in addition to this regulation, the fuel nozzle is constructed so that the suction produced by the engine operates to automatically regulate the resistance to the flow of the fuel through the nozzle in such a manner as to maintain a mixture of the proper proportions of air and fuel under the varying demands of the engine. The carbureter is also provided with a centrifugal dust collector which thoroughly frees the air from dust before the air enters the mixing chamber. The several features mentioned can be combined or arranged in various ways to produce the results stated, so that the invention is not limited to the constructions of the carbureter illustrated in the drawings.

In the accompanying drawings: Figure 1 is a central sectional elevation of a carbureter embodying the invention. Fig. 2 is a plan view thereof on a reduced scale. Fig. 3 is a fragmentary plan view showing the air supply valve closed. Fig. 4 is a horizontal section on a reduced scale in line 4-4, Fig. 1. Fig. 5 is a fragmentary sectional plan, on a reduced scale in line 5-5, Fig. 1. Fig. 6 is a fragmentary horizontal section on line 6-6, Fig. 1. Figs. 7 and 8 are horizontal sections, on a reduced scale, on lines 7-7 and 8-8, respectively, of Fig. 1. Fig. 9 is an enlarged section of the fuel supply nozzle and associated parts. Fig. 10 is a fragmentary sectional elevation on line 10-10, Fig. 8. Fig. 11 is a fragmentary horizontal section on line 11-11, Fig. 1. Fig. 12 is a section of a fuel supply nozzle of modified construction.

Like reference characters refer to like parts in the several figures.

A represents the outer casing of the carbureter, B a reservoir or float chamber which contains the gasoline or other liquid fuel, C an air supply passage, D a carbureting or mixing chamber in which the liquid fuel is discharged by a fuel supply nozzle E is mixed with the air, and F a discharge pipe or passage leading from the mixing chamber to the engine cylinder.

Preferably the mixing chamber D, which is circular in cross-section, is arranged concentrically within the casing A and forms therewith an annular chamber which constitutes the air supply passage C, to which the air is admitted through inlet openings c at the upper portion thereof. The float chamber B is located in the bottom of the casing below the mixing chamber, and the fuel supply nozzle extends from the float chamber axially into the lower end of the air supply passage which is of conical or funnel form. A preliminary carbureting or mixing chamber G extends centrally up into the main mixing chamber D from the bottom thereof concentrically with the fuel nozzle and communicates by its open lower end with the air supply passage C and by openings in its side walls with the main mixing chamber. The discharge pipe connects axially with the top of the mixing chamber. The suction produced by the operation of the engine draws the air through the air supply passage C past the fuel supply nozzle and up through the preliminary mixing chamber G into the main mixing chamber D. The fuel which is drawn from the fuel nozzle E by the suction of the air is vaporized and mixed with the air in the preliminary and main mixing chambers to produce the explosive mixture, which passes to the engine through the discharge pipe F. Means are provided for causing the air to whirl or rotate rapidly in the funnel-shaped lower end of the air supply passage about the discharge orifice of the fuel supply nozzle and also in the main mixing chamber. This concentric arrangement of the parts is especially suited to a carbureter embodying the invention, makes the carbureter compact and facilitates the manufacture thereof. The invention is not, however, restricted to such concentric arrangement of the parts as will hereinafter appear.

In the preferred construction of the carbureter, shown in Figs. 1 to 11 of the drawings, the casing A is composed of an upper inverted cupped shell α , an intermediate cupped shell α' having a tapering or conical bottom and fitting tightly in the open lower end of the upper shell, and a lower cupped shell α'' fitting tightly on the lower end of the intermediate shell. The float chamber α''' is formed by the lower shell α'' and the

bottom of the intermediate shell. The supply of liquid fuel is controlled to maintain the required liquid level in the float chamber, as usual, by a suitable valve b in the fuel supply pipe b' actuated by a float b'' through levers b''' or other connections.

The mixing chamber D, which is cylindrical or of circular cross-section, is formed by upper and lower cupped shells d d' arranged with their meeting open ends fitting tightly one within the other. The bottom of the mixing chamber is tapered correspondingly with the bottom of the intermediate shell of the outer casing whereby the lower end of the annular air supply passage converges downwardly toward the fuel nozzle E. The upper portion of the mixing chamber D is preferably surrounded by a jacket d'' through which the engine exhaust, or other heating medium, is circulated for heating the walls of the mixing chamber. This jacket is formed by an upper enlarged end d''' of the lower shell d' of the mixing chamber and a cupped shell d''' fitting tightly therein, and is provided with nipples d'''' for connection with circulating pipes for the heating medium.

The fuel discharge nozzle, see Fig. 9, is screwed into a flanged nut or collar e and has a flange e' at its lower end which engages an internal shoulder e'' on a tube e''' which surrounds the nozzle in the float chamber. By screwing the nozzle into the collar e the edge of the opening in the bottom of the air supply passage through which the nozzle projects is clamped between the flange of the collar e and the upper end of the tube e''' whereby the nozzle is securely held. The operating levers b''' for the fuel supply valve b are fulcrumed in slots in the tube e''' . The lower end of the tube e''' extends through the bottom of the float chamber and has a nipple or connection e'''' for the fuel supply pipe screwed thereon, the joint between this nipple and the bottom of the float chamber being suitably packed to prevent leakage from the float chamber. The discharge pipe F is provided with a throttle valve f of any suitable construction.

The preliminary carbureting or mixing chamber G is formed by a cupped shell g which communicates by its open lower end with the air supply passage and by openings g' in its sides with the main carbureting or mixing chamber D. The lower end of the shell g is connected to the bottoms of the mixing chamber and of the air supply passage C, as by an enlarged or shouldered part g'' on which the bottom of the mixing chamber bears, and by fastening tongues g''' which pass through slots in the bottom of the air passage and are clenched on the underside thereof; and a central stay rod or bolt g'''' secured to the upper end of the shell g extends up through the discharge

pipe F and is provided at its upper end with a nut g^5 . The mixing chamber D is provided at its top with a collar g^6 which fits in the lower end of the discharge pipe F, and the upper ends of the shells forming the outer casing and the heating jacket d^2 are clamped between the top of the mixing chamber and the end of the discharge pipe, so that by tightening the nut g^5 the shells 10 of the outer casing, the mixing chamber D and the heating jacket are drawn tightly together and firmly held in place. By thus making the parts of complementary cupped shells they can be formed by drawing from 15 sheet metal, which lessens the cost of manufacture of the carbureter, and when the stay rod g^4 is released the parts can be readily separated, thus affording access to the interior thereof. This construction is therefore 20 desirable, but any other suitable construction of the parts and means for connecting them can be employed.

The rotation of the air about the fuel nozzle is preferably caused by oblique or 25 tangential vanes H which surround the nozzle in the funnel-shaped lower end of the air supply passage C and are conveniently formed by slitting the lower end of the shell g of the preliminary mixing chamber 30 and bending portions thereof obliquely inward.

The movement of the air through the converging or funnel-like lower portion of the air passages produces a concentration or 35 pressure thereof which increases as the air approaches the fuel nozzle and this pressure of the air, together with the rapid rotation of the air due to the oblique vanes H, causes a cyclone-like action causing a suction about 40 the discharge orifice of the nozzle which draws the liquid fuel from the nozzle and violently agitates it in the preliminary mixing chamber, thus breaking it up very finely and mixing it with the air. The air and 45 atomized fuel pass from the preliminary mixing chamber through the openings g' and are delivered tangentially into, and are caused to continue rotating in the same direction in the main mixing chamber D by 50 curved vanes or plates I which extend outwardly and forwardly in the main mixing chamber from the rear edges of the openings g' in the walls of the preliminary mixing chamber. These vanes or plates I, in 55 the construction shown, are held between the bottom of the main mixing chamber and a cap plate i which is secured on the top of the preliminary mixing chamber by the stay rod g^4 , and they have securing extensions at 60 their inner ends which bear against the walls of the preliminary mixing chamber and are confined by flanges or portions i' and i^2 of the cap i and the bottom of the 65 main mixing chamber surrounding their upper and lower ends.

The rapidly rotating mixture in the mixing chamber D causes the unvaporized liquid fuel to be thrown outwardly against the cylindrical wall of the chamber where it spreads and rotates with great velocity. 70 The carbureted air having the unvaporized liquid fuel thus eliminated, is displaced inwardly and drawn off through the axial discharge outlet F. The unvaporized liquid fuel being thus detained, rotates with 75 great velocity upon the wall of the cylinder and is forced to flow through opening K into the passage k by which it is returned to the fuel supply by means of the following factors: The drive or centrifugal action of 80 the liquid as it rotates upon the wall of the mixing chamber, gravity, a lower pressure at the nozzle than that of the mixing chamber due to the drive or injector action of the air at its orifice, and the injector action of 85 the incoming liquid supply in the nozzle.

As shown in Figs. 1 and 10, the return pipe connects with an annular channel k' which surrounds the nozzle B and is connected by a passage k^2 with the discharge 90 orifice of the nozzle, so that the fuel nozzle acts by the injector action to draw the fuel partly from the float chamber and partly from this returned excess supply. The discharge of new fuel from the float chamber 95 B is therefore regulated or affected by the quantity of excess fuel returned from the mixing chamber to the fuel supply nozzle. By thus separating the unvaporized liquid fuel from the explosive mixture and returning it to the supply to be again used, the discharge orifice of the nozzle can be made 100 large enough to supply the requisite fuel for the maximum quantity of explosive mixture demanded by the engine and the 105 fuel will not be wasted or the cylinder fouled if the quantity of fuel supplied is in excess of what is needed under the varying running conditions. As the cylindrical wall of the mixing chamber is heated and 110 the excess fuel is circulated and repeatedly subjected to this heat and to the frictional contact of the rapidly rotating mixture in the mixing chamber, the vaporization of the fuel is practically complete. 115

In order to regulate the supply of fuel in accordance with the supply of air so as to maintain an explosive mixture of substantially the same proportions of air and fuel for all suction, the fuel nozzle E, in the 120 construction shown in Figs. 1-11, is provided with a tangential inlet orifice L, see Fig. 11. The tangential inlet causes the liquid fuel to rotate in the chamber or bore 125 L of the nozzle from which the fuel escapes through the axial discharge orifice. This construction of the nozzle compensates for the difference in the laws which control the flow of the liquid and the air in a carburetor, which may be stated as follows: The flow of 130

- the gasoline in a tube is proportional to the difference in pressures at the two ends of the tube. The flow of air in a carbureter is, however, governed by a different law, as air flowing from a source at one pressure into a receiver at a lower pressure expands, and a portion of the energy which produces the flow is used in producing this expansion. The flow of air is consequently proportional to the square root of the difference between the squares of the absolute pressures of the outside atmosphere and of the air in the carbureter at the discharge orifice of the fuel nozzle. If the area of the air opening under various suctions, which is obviously the measure of the resistance, is proportional to the square of the suctions, the correct proportioning of the explosive mixture for all suctions is obtained.
- Since the rotation of the liquid in the cylindrical bore of the nozzle is proportional to the flow of the liquid through the bore and the centrifugal force of the rotating liquid is as the square of the revolutions, the described construction of the nozzle causes a resistance to the flow of the liquid through the discharge orifice which is as the square of the flow, and inasmuch as the flow is proportional to the suction, the resistance to the liquid flow is proportional to the square of the suctions. As this centrifugal factor in the liquid flow compensates for the resistance to the flow of the air due to expansion, the expansion being as the square of the suction, the proper proportions of the air and fuel in the explosive mixture are maintained for all suctions by the described construction of the fuel nozzle E. A similar action can also be secured by other constructions. For instance, the nozzle can be provided with a helical flow passage l' formed by a helically threaded core in the nozzle bore, as shown in Fig. 12. This compensation does not, however, apply to capillary or "skin" resistance to the flow of the two elements. As the capillary resistance to the flow of the liquid fuel is lessened by increasing the size of the nozzle passage, the centrifugal resistance to the flow of the liquid has another advantage in that it makes it possible to use a larger flow passage through the fuel nozzle. The nozzle orifice can be made so large that it will not be clogged or affected by dirt or water in the fuel, which is a great source of trouble in many carbureters in which the discharge orifice of the fuel supply nozzle must be very small. With the excess fuel returning through the nozzle as explained, and provision for creating the centrifugal resistance, a discharge orifice of over one-sixteenth of an inch in diameter has been successfully used.
- M represents the centrifugal dust collector, which preferably surrounds the upper portion of the air supply passage or cham-

ber C and comprises an annular separating chamber m and an annular dust chamber or pocket m' below the separating chamber. The separating chamber is provided at its upper outer portion with air admission openings m² and with oblique or tangential vanes m³ which cause the air to rotate in this chamber so that the dust will be thrown outwardly by centrifugal force and separated from the air which passes through the inlet openings in the casing A into the air supply passage C. The dust settles to the bottom of this chamber and passes through holes m⁴ therein into the dust chamber m' which has dust discharge holes m⁵ which are normally closed by a valve or ring m⁶ and are adapted to be opened to discharge the dust by turning said ring. The inlet openings c to the air supply passage are preferably covered by a screen which aids in the separation of the dust. The air rotating in the separating chamber outside of the screen prevents the dust from collecting thereon and clogging the screen as it is apt to do in the case of a simple filtering screen.

The dust collector is preferably constructed as shown, the separating chamber being formed by an inverted cupped shell m⁷ inclosing the upper end of the carbureter casing and a cupped ring m⁸ fitting in the shell, and the dust chamber being formed by an outwardly projecting flange m⁹ at the lower end of the top shell of the casing and the cupped valve ring which rests on said flange m⁹ and fits loosely on the enlarged lower end of the shell m⁷. The shell m⁷, like the upper shells of the casing A, and the heating jacket are held between the top of the mixing chamber D and the lower end of the discharge pipe F.

m¹⁰ is a valve which fits loosely on the top of the dust collector and has holes m¹¹ adapted to register with the air admission openings m² and is provided with a handle m¹² for turning it. By adjusting this valve the air supply to the carbureter can be regulated as required.

The described construction of the dust collector is desirable as the parts thereof can all be made by drawing from sheet metal, and the concentric arrangement of the dust collector around the casing is well adapted to a carbureter such as described, in which the air is caused to rotate in the air supply passage and mixing chamber, and makes the carbureter compact, but other constructions and arrangements of the dust collector could be used.

I claim as my invention:

1. In a carbureter, the combination of air supply means, a liquid fuel supply nozzle, a carbureting chamber located close to said fuel nozzle and into which said fuel and air are directly discharged and in which the air is carbureted, said chamber having a cir-

- cular wall and being provided with non-driven means for causing the air and fuel to rotate therein and with an outlet for the explosive mixture which is located inwardly from said circular wall whereby the unvaporized liquid is thrown outwardly against said circular wall and is trapped in the carbureting chamber, and a normally open passage which leads from said chamber to said nozzle and through which the unvaporized liquid flows from the carbureting chamber back to said fuel supply nozzle, substantially as set forth. 70
2. In a carbureter, the combination of air supply means, a liquid fuel supply nozzle, a carbureting chamber in which the air is carbureted by contact with the liquid fuel having a circular wall and provided with stationary members for causing the air and fuel to rotate therein and with an outlet for the explosive mixture which is located inwardly from said circular wall whereby the unvaporized liquid is thrown outwardly against said circular wall and is trapped in the carbureting chamber, and a normally open passage leading from said chamber to said nozzle for returning said unvaporized fuel to the fuel supply nozzle, substantially as set forth. 80
3. In a carbureter, the combination of air and liquid fuel supply means, a carbureting chamber of circular cross-section, means for causing the mixture of air and fuel to rotate in said carbureting chamber for separating the unvaporized liquid from the mixture, and means for regulating the fuel supply by the separated liquid, substantially as set forth. 85
4. In a carbureter, the combination of air and liquid fuel supply means, means for separating the unvaporized liquid from the mixture of air and fuel, and means for regulating the fuel supply by the separated liquid, substantially as set forth. 90
5. In a carbureter, the combination of a main liquid fuel supply means, air supply means, means for separating the unvaporized liquid from the mixture of air and fuel, and means for returning the separated liquid to the fuel supply means for regulating the supply of fuel from said main supply means, substantially as set forth. 95
6. In a carbureter, the combination of air supply means, a liquid fuel supply nozzle, a carbureting chamber having a tangential inlet and an axial outlet whereby the air and fuel are caused to rotate in said carbureting chamber and the unvaporized fuel is separated from the mixture, and means for returning the separated liquid to the fuel supply nozzle for regulating the discharge of new liquid therefrom, substantially as set forth. 100
7. In a carbureter, the combination of air supply means, a liquid fuel supply nozzle, means for separating the unvaporized liquid from the mixture of air and fuel, and means for returning the separated liquid to the fuel supply means for heating the circular wall of said carbureting chamber, substantially as set forth. 105
8. In a carbureter, the combination of air and liquid fuel supply means, a carbureting chamber of circular cross-section, and means for causing the mixture of air and fuel to rotate in said carbureting chamber for separating the unvaporized liquid from the mixture, means for returning the separated liquid to the fuel supply means, and means for heating the circular wall of said carbureting chamber, substantially as set forth. 110
9. In a carbureter, the combination of a carbureting chamber, means for causing the mixture to whirl therein, a liquid fuel supply nozzle located axially with reference to said carbureting chamber, a converging air supply passage and deflecting members by which the entire air supply is delivered toward said nozzle in a direction opposed to the direction of discharge from the nozzle and is caused to rotate about the discharge orifice of the nozzle, substantially as set forth. 115
10. In a carbureter, the combination of a carbureting chamber, means for causing the mixture to whirl therein, a liquid fuel supply nozzle located axially with reference to said carbureting chamber, an air supply passage having a funnel-shaped portion which converges toward said nozzle in a direction opposite to the direction of discharge of said nozzle, and means for causing the air to rotate in said converging portion of the air supply passage about said nozzle, substantially as set forth. 120
11. In a carbureter, the combination of a liquid fuel supply nozzle, an air supply passage having a funnel-shaped portion which converges toward said nozzle, and vanes arranged tangentially in said converging portion of the air supply passage around the nozzle for causing the air to rotate about the nozzle, substantially as set forth. 125
12. In a carbureter, the combination of a fuel supply nozzle, an air supply passage, a cylindrical chamber having a tangential inlet and an axial outlet, and a preliminary carbureting chamber arranged within and through which the air and fuel pass to said cylindrical chamber, substantially as set forth. 130
13. In a carbureter, the combination of a fuel supply nozzle, an air supply passage having means for causing the air to rotate about said nozzle, a cylindrical chamber having a tangential inlet and an axial outlet, and a preliminary carbureting chamber arranged concentrically with said nozzle and through which the air and fuel 135

- pass to said cylindrical chamber, substantially as set forth.
14. In a carbureter, the combination of a carbureting chamber arranged concentrically 5 therein and forming an annular air supply passage, a fuel supply nozzle arranged axially at one end of said passage, tangential vanes in said passage around said nozzle, a chamber arranged centrally in said carbureting chamber and communicating at 10 one end with said passage and by side openings with said carbureting chamber, and vanes for causing the air and fuel to rotate in said carbureting chamber, substantially 15 as set forth.
15. In a carbureter, the combination of an air supply passage, a chamber of circular cross-section located therein, a preliminary carbureting chamber extending centrally 20 into said circular chamber and communicating at one end with said air supply passage and by openings in its side walls with said circular chamber, a fuel supply nozzle located in said air passage axially with respect to said preliminary carbureting chamber, vanes in said air supply passage for causing the air to rotate about said fuel supply nozzle, and vanes extending from 25 said preliminary carbureting chamber into said circular chamber for causing the air and fuel to rotate in said circular chamber, substantially as set forth.
16. In a carbureter, the combination of a carbureting chamber, means for causing the 35 mixture to whirl therein, an axial outlet, a fuel supply nozzle, an air supply passage surrounding said carbureting chamber, and a heating jacket surrounding said carbureting chamber in said air supply passage, substantially as set forth.
17. In a carbureter, the combination of a carbureting chamber of circular cross-section, a fuel supply nozzle, a heating jacket surrounding said carbureting chamber, an 45 air supply passage surrounding said heating jacket, and means for causing the air and fuel to rotate in said carbureting chamber, substantially as set forth.
18. In a carbureter, the combination with 50 fuel supply means, of a dust collector through which the air passes to the carbureter and which is provided with means for causing the air to rotate therein, and means for causing the air to continue in rotation in the same direction in the carbureter, substantially as set forth.
19. In a carbureter, the combination with 55 fuel supply means, of a dust collector through which the air passes to the carbureter and which is arranged concentrically with respect to the carbureter and is provided with means for causing the air to rotate therein, and means for continuing the rotation of the air in the carbureter, substantially as set forth.
20. In a carbureter, the combination with fuel supply means, of a dust collector through which the air passes to the carbureter and which surrounds the carbureter and is provided with means for causing the air to rotate therein, and means for continuing the rotation of the air in the carbureter, substantially as set forth.
21. In a carbureter, the combination with 75 fuel supply means, a carbureting chamber in which the air and fuel are caused to rotate, of a dust collector through which the air passes to the carbureting chamber having an annular separating chamber surrounding said carbureting chamber and provided with an air inlet disposed so as to cause the air to rotate therein and with an air outlet in its inner wall, substantially as set forth.
22. In a carbureter, the combination with 80 fuel supply means, and an air passage in which the air is caused to rotate, of a dust collector through which the air passes to the carbureter having an annular separating chamber arranged concentrically with respect to the carbureter and provided with means for causing the air to rotate therein and with an air outlet leading to said air passage, substantially as set forth.
23. In a carbureter, the combination with 85 fuel supply means, and an air supply passage of circular cross-section in which the air rotates, of a dust collector through which the air passes to the carbureter surrounding said air supply passage, said dust collector having means for causing the air 90 to rotate therein, and an air outlet opening in its inner wall leading to said air supply passage, substantially as set forth.
24. In a carbureter, the combination with 95 fuel supply means, and a chamber of circular cross-section in which the air is caused to rotate, of a dust collector through which the air passes to said circular chamber, comprising a separating chamber of circular cross-section having air inlets arranged to 100 cause the air to rotate therein and an air outlet located inwardly from the outer circumference of said chamber, and a valve controlling said air inlet openings which is adjustable to regulate the supply of air to 110 the carbureter, substantially as set forth.
25. In a carbureter, the combination with 105 fuel supply means, of a carbureting chamber of circular cross-section having means for causing the mixture to whirl therein, an air supply passage, and a heating jacket surrounding and concentric with said carbureting chamber, and a discharge pipe for 120 the mixture arranged concentrically with respect to said carbureting chamber, and a stay rod which detachably secures said parts together.
26. In a carbureter, the combination with 125 fuel supply means, a carbureting chamber of circular cross-section having means for 130

causing the mixture to whirl therein, an air supply passage concentric with and surrounding said carburetor chamber, said carbureting chamber and supply passage being formed by complementary separable shells, and means for securing said shells together, substantially as set forth.

27. In a carburetor, the combination with fuel supply means, of a carbureting chamber of circular cross-section, an air supply passage, a heating jacket, and a discharge pipe for the mixture arranged concentrically

with respect to each other, said carbureting chamber, air passage and heating jacket each formed by complementary separable shells, and a central stay rod for securing said shells together, substantially as set forth. 15
